UNITED STATES PATENT OFFICE.

FLORENCE I. LEONARD, OF ARLINGTON, GEORGIA.

TRAVELING-CASE.

SPECIFICATION forming part of Letters Patent No. 514,827, dated February 6, 1894.

Application filed September 7, 1893. Serial No. 485,039. (No model.)

To all whom it may concern:

Be it known that I, FLORENCE I. LEONARD, of Arlington, in the county of Calhoun and State of Georgia, have invented a new and 5 useful Improvement in Traveling-Cases, of which the following is a specification.

My invention is an improved traveling case which will be especially useful to ladies as well as to gentlemen for short trips and the 10 invention seeks to provide a simple inexpensive case which will be convenient to carry, has apartments to properly contain several dresses, lingerie, hats and the like sufficient for a trip of a few days and the invention consists in the novel constructions and combinations of parts, as will be hereinafter described and pointed out in the claims.

In the drawings—Figure 1 is a perspective view and Fig. 2 a front view of the case the 15 cover or top section being raised, and Fig. 3 is an end view of the case the several covers being raised.

The main compartment A is a box of sufficient length, width and depth to hold several 20 dresses, ordinarily two feet long, sixteen inches wide and nine inches high, and is sufficient to hold two dresses. This box may be termed the dress box and like the other parts of the case may be made of leather suitably 25 braced or may be formed of other materials suitable for the purpose.

To the box A is hinged at one edge b the cover or top section B, having at its other or swinging edge suitable fastening means 30 by which it may be held closed.

Upon the cover B I mount at both ends hat boxes C C separated at their adjacent edges affording an intermediate space in which is arranged the handle D fixed to the lid B and 35 adjacent to the handle D is provided a card case E and pencil clasps F.

Upon the cover B in rear of the hat boxes C is provided a long narrow box G extending the length of the cover and having a cover g upon the outer side of which are secured the 40 umbrella or cane straps H.

The lids C' C' of the hat boxes are provided on their under sides one with a manicure case with spacings for the fittings of such cover, 45 and the other with a mirror while upon the inner side of the lid B is provided a pocket for stationery. The long narrow box G is adapted for lingerie, &c.

Having thus described my invention, what I claim as new, and desire to secure by Letters Patent, is—

1. A traveling case comprising a box or main compartment, the cover therefor and the hat boxes mounted upon the opposite ends of said cover and having lids substantially as set forth.

2. An improved traveling case having the main compartment or box and the lid thereof provided with hat boxes upon its ends and with the long lingerie box extended along- 65 side the hat boxes substantially as set forth.

3. An improved traveling case consisting of the main box the lid or cover therefor provided on its upper side centrally between its ends with the handle and the hat boxes fixed 70 upon the ends of said cover on opposite sides of the handle and having lids substantially as and for the purposes set forth.

4. The improved traveling case herein described consisting of the main box or compartment the lid thereof having upon its opposite ends hat boxes separated at their adjacent edges affording space for the handle, the handle secured to the lid between the hat boxes and the lingerie box secured upon said 80 lid at one edge thereof and extended alongside the hat boxes the said hat and lingerie boxes being provided with lids substantially as and for the purposes set forth.

5. In a traveling case the combination with 85 the main box or compartment and its lid having the handle between its ends and having the hat boxes mounted on the lid and provided on their upper sides with independent lids and also having the lingerie box provided 90 with an independent lid and extended alongside the hat boxes all substantially as described whereby access may be had to the interior of the main box without opening either of the hat or the lingerie boxes or to any one 95 of the latter boxes without opening the main box all substantially as and for the purposes set forth.
